UNITED STATES PATENT OFFICE.

ANNA SHERIDAN JEFFRIES, OF CLEARMONT, WYOMING.

DESIGN FOR A CAP.

58,384.

Specification for Design.

Patented July 12, 1921.

Application filed December 2, 1920. Serial No. 427,922. Term of patent 3½ years.

To all whom it may concern:

Be it known that I, ANNA SHERIDAN JEFFRIES, a citizen of the United States, residing at Clearmont, in the county of Sheridan and State of Wyoming, have invented a new, original, and ornamental Design for Caps, of which the following is a specification, reference being had to the accompanying drawing, forming part thereof.

The figure is a plan view of a cap, showing my new design.

I claim:

The ornamental design for a cap as shown.
ANNA SHERIDAN JEFFRIES.
